UNITED STATES PATENT OFFICE

JOHN J. FLANIGAN, OF OAK PARK, ILLINOIS

DUPLICATING MACHINE

Application filed April 10, 1929. Serial No. 353,918.

This invention relates to the duplicating art wherein an imprint of an original writing or the like is made on a gelatin transfer pad from which copies are made by impressing 5 sheets successively thereon.

The principal object of the invention is to provide the gelatin in the form of tablets or pads of convenient size capable of being used either as individual units or in conjunction 10 with a machine to form the impression bed of the machine.

Another object of the invention is to provide a duplicating machine which is especially adapted for the use of the individual 15 gelatin tablets.

Another object of the invention is to provide a self-contained duplicating machine in which the individual gelatin tablets are stored in condition for instant use and in the 20 proper order of use.

Another object of the invention is to provide a duplicating machine having a removable impression bed in the form of flat detachable unit gelatin tablets capable of use 25 apart from the machine.

Another object of the invention is to provide a compact readily portable duplicating machine having the capacity for a number of changes or renewals of gelatin impression 30 surfaces to meet a general demand for a machine of moderate cost.

Another object is to provide a gelatin impression plate or tablet which is inexpensive to manufacture and which can be sold commercially and used as a unit apart from the 35 duplicating machine.

The drawings show a selected embodiment of my invention, and referring thereto

Fig. 1 is a side elevation of a duplicating 40 machine embodying the invention.

Fig. 2 is a top plan view of the machine shown in Fig. 1 with one of the gelatin tablets in operating position on the frame of the machine.

Fig. 3 is an enlarged view in section on line 45 3-3 of Fig. 2; and

Fig. 4 is a perspective view of one of the impression gelatin tablets.

The duplicating machine shown in the 50 drawings comprises a frame A and a carriage

B reciprocable on the frame. The frame itself comprises a rectangular box-like structure formed to provide an inclosure or cabinet for the storage of individual gelatin impression tablets. This frame has end walls 55 1, a side wall 2 and a top 3, the other side wall being omitted to permit the gelatin tablets to be conveniently inserted or removed from the storage compartment formed beneath the top and between said walls. In 60 this structure the frame is made as a casting although for the purpose of my invention it may be made of sheet metal, wood, or other suitable material. The frame has strengthening ribs 2', 3', on the inside of the side wall and on the under side of the top wall. At the open side of the frame the corners 4 are rounded to form posts and to finish off the edges of the opening. This cabinet frame may be as high as is necessary to provide a 65 required capacity for the storage of gelatin tablets; it is intended to be placed on a table or other suitable support and this support may be made in the form of a sectional cabinet having additional storage space for gelatin 70 tablets depending upon the requirements of the particular user. The top wall 3 of the frame forms a bed plate for supporting the gelatin tablet C, Fig. 2. Any suitable means may be provided for holding the gelatin tablets 75 separate from each other within the storage compartment in the frame. In the drawings I have shown a series of parallel standing flanges 7 mounted on the end walls in horizontal position to form guide rests one 80 above the other to receive and support the tablets which are inserted in and removed from the cabinet frame laterally through the open side thereof. Gelatin used for duplicating purposes is generally maintained soft 85 and in proper condition by moisture applied by wetting the gelatin surface. This is done generally when the gelatin is stored away after use. The purpose in making the cabinet frame forms an inclosure for the tablets 90 stored therein and tends to retard evaporation of the moisture sufficiently to prevent the gelatin from drying or hardening while its surface is becoming re-useable.

In the machine shown in the drawings, 95

Figs. 1 and 2, a carriage B is mounted to travel back and forth above a tablet on the bed, and also to feed the sheets to be imprinted and to strip them from the impression surface. The carriage herein shown carries the paper chute 9, the platen roller 10, and the grip roller 11, and it is fully set forth and claimed in my co-pending application Serial No. 344,203, filed March 5, 1929. 5
10 This carriage comprises a bar 12 whose end 14 is mounted upon a sleeve 15 on the guide rod 13 as disclosed in said co-pending application. This sleeve has rollers 16 at each end radially disposed with respect to the 15 guide rod and adapted to operate thereon so that the carriage may be easily moved back and forth. The sleeve is rotatable about the guide rod 13 so that the entire carriage may be swung upwardly clear of the impression bed of the machine to permit insertion and 20 removal of the tablets. The guide rod 13 is bolted at its ends 17 to the laterally turned ends 18 of a bar 18' which is bolted to the side wall of the frame. The rear end of this 25 supporting bar extends considerably beyond the rear end of the frame to accommodate the carriage and enable the platen roller to travel the full length of the impression surface of the gelatin tablet. The opposite end 30 of the carriage bar 12 is turned downwardly at 19 and carries a roller 20 which rides on the trackway formed by a strap member 21 which extends from the front end of the frame to a point beyond the rear end of the 35 frame and is then turned angularly downwardly at 22 and bolted to the corner of the frame, this diagonal portion 22 serving as a brace to support the extended end of the trackway. The end of the trackway is extended beyond the frame for the same reason that the guide rod is extended, namely, to 40 enable the platen roller to travel the full length of the impression surface of the gelatin tablet. The roller 20 forms an easy operating bearing for this end of the carriage and at the same time does not interfere with the carriage being swung on the guide rod as previously mentioned. 45

An end margin bar 23 is mounted on the 50 frame across the front end thereof to serve as a stop for registering the sheet of paper 24 in impression position. In the type of platen carriage shown the platen roller 10 and the grip roller 11 co-operate to grip the sheet between them and to feed it on to the gelatin surface on the impression stroke of the carriage, and to strip the sheet from the gelatin surface on the return stroke of the carriage. The platen roller is mounted at the ends of 55 the side arms 25 of a yoke 26 which is pivoted at 27 on the carriage and provided with a handle 28 whereby the yoke may be swung upwardly to separate the platen roller from the grip roller and permit insertion of the 60 sheet to be printed between the rollers.

The unit gelatin table C, Fig. 4, is preferably rectangular in shape and of a size to conform to the bed plate of the machine. This tablet comprises a backing or supporting plate 30 having a film or layer of gelatin 31 on one side thereof. This backing plate may be made of any suitable material and should be stiff enough to maintain the surface of the gelatin practically flat throughout its area. In addition to this it should be sufficiently rigid to stand the necessary handling incident to its use and the usual packing and shipping conditions. I prefer to make the backing member of a suitable thickness of waterproof press board because press board 70 satisfactorily meets the requirements and is comparatively inexpensive. The gelatin film or layer 31 is of substantially uniform thickness throughout its area and may be applied to the backing member in sheet form and cemented thereto, or it may be molded on the backing, or it may be heated and poured upon the backing, or the backing may be molded integral with the gelatin so as to provide a stiffening reinforcement for the 75 gelatin layer. The ends 32 of the gelatin layer are preferably brought close to the ends of the backing member 30 slight margins 33, however, being left so that the backing member 80 will serve as a protection to the ends of the gelatin layer and also so that the gelatin layer may be brought close to the margin bar 23. The edges and corners of the gelatin layer are preferably rounded or slightly beveled to finish off these edges and to arrange 85 them less liable to damage. Wider side margins 34 of the backing member are provided between the side edges of the gelatin and the edges of the backing to provide sufficient room beyond the gelatin layer for the means 90 of attaching the tablet to the bed plate of the machine. These side margins have key-hole slots 35 which are engaged by upstanding studs 36 on the bed. These studs have overhanging heads 37 to form hooks, Fig. 3, to 95 lock the tablet in position on the bed. In positioning the tablet it is arranged on the bed with the slots engaging the studs and then the tablet is shifted laterally until the 100 studs enter the narrow portion of the key-hole slots. The overhanging heads 37 then engage the top of the backing and retain the tablet in its proper position. I prefer to provide the locking studs at one side of the 105 frame and lock the opposite edge of the tablet by spring clips 39 bolted at 40 to the side of the frame and overhanging the bed plate. By providing keyhole slots 35 on each side 110 margin of the backing board with their enlarged ends 38 inwardly directed the tablet 115 may be used end for end, which is a convenience, and it may be reversed as required to facilitate the use of the entire area of the 120 gelatin surface. Ordinarily the imprint on 125 the gelatin surface will be located adjacent 130

the margin bar and a small imprint may leave a considerable gelatin surface clear; by reversing the tablet this clear surface will be brought into position for receiving an imprint in juxtaposition to the margin bar. The tablet forms a simple and convenient means for handing and using the gelatin material which, as is well known, is easily damaged. The backing forms a protecting margin about the gelatin and enables the tablet to be handled and inserted in the machine and storage cabinet and removed therefrom without touching the gelatin. The tablet is light in weight, it is in a flat and convenient form and shape for use and it may be readily arranged in proper position on the bed of the machine and removed therefrom, and can also be readily inserted in and removed from the storage cabinet.

I have shown the invention in a simple form which I have found satisfactory in accomplishing the desired results but I am aware that changes in the form, construction and arrangement of parts may be made without departing from the spirit or sacrificing the advantages of the invention to adapt it for different conditions and for other purposes, and I reserve the right to make all such changes as fairly fall within the scope of the following claims.

I claim:

1. The combination of a frame having a supporting bed, a substantially L-shaped margin bar fixed at one end of the bed, a gelatin tablet on said bed, and means for detachably holding the tablet in operative relation to the margin bar.
2. The combination of a frame having a supporting bed, a substantially L-shaped margin bar fixed at one end of the bed, a gelatin tablet on said bed and having openings therein and means on said bed engaging said openings to hold the gelatin tablet in operative relation to said margin bar.
3. The combination of a frame having a supporting bed, studs upstanding from said bed, and a gelatin impression tablet detachably engageable with said studs for retaining the tablet in said bed.
4. The combination of a frame having a supporting bed, studs upstanding from said bed adjacent one side thereof, clips adjacent the side of the bed, and a gelatin impression tablet adapted to engage said clips and having openings to receive said studs for holding the tablet in position on the bed.
5. In a duplicating machine which has a bed having a flat gelatin impression tablet detachably mounted thereon and a carriage movable over the bed in operative relation to said tablet, the combination of a frame supporting said bed and having a compartment therein, and means in said compartment for supporting flat gelatin impression tablets detached from said bed.

6. In a duplicating machine which has a bed having a flat gelatin impression tablet detachably mounted thereon and a carriage movable over the bed in operative relation to said tablet, the combination of a frame supporting said bed having a compartment therein open at one side, substantially U-shaped rails extending along opposite walls of said compartment from said open side and providing supports adapted to receive flat gelatin impression tablets when detached from said bed.

JOHN J. FLANIGAN.
